US0D1034428S

(12) **United States Design Patent** (10) **Patent No.:** **US D1,034,428 S**
(45) **Date of Patent:** **** Jul. 9, 2024**

(54) **PHOTOVOLTAIC DEVICE**

(71) Applicant: **Dongguan CHY Power Technology CO., LTD**, Dongguan (CN)

(72) Inventor: **Huaguo Zhang**, Huaihua (CN)

(73) Assignee: **Dongguan CHY Power Technology Co., LTD**, Dongguan (CN)

(**) Term: **15 Years**

(21) Appl. No.: **29/859,919**

(22) Filed: **Nov. 15, 2022**

(51) LOC (14) Cl. **13-02**

(52) U.S. Cl.

USPC **D13/102**

(58) **Field of Classification Search**

USPC D13/103, 107, 119, 152, 158, 177, 184
CPC H01R 13/52; H01R 13/6675; H01B 1/50;

H02J 7/00; G06F 1/1632

(57) **CLAIM**

The ornamental design for a photovoltaic device, as shown and described.

DESCRIPTION

FIG. 1 is a front, right and top perspective view of a photovoltaic device, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the photovoltaic device that form no part of the claimed design.
